UNITED STATES PATENT OFFICE.

DANIEL P. JORDAN, OF BURNS, OREGON.

BORING-MACHINE.

1,079,650.

Specification of Letters Patent.

Patented Nov. 25, 1913.

Application filed May 26, 1911. Serial No. 629,688.

To all whom it may concern:

Be it known that I, DANIEL P. JORDAN, a citizen of the United States, residing at Burns, in the county of Harney and State 5 of Oregon, have invented certain new and useful Improvements in Boring-Machines, of which the following is a specification.

My invention relates to a multiple bit boring machine for making lock mortises in the 10 edge of doors.

The object of my invention is to provide a boring machine with means for readily adjusting the bits to aline with the center 15 of the edge of the door and which may be used upon doors of various thicknesses.

A further object of my invention is to provide novel means for connecting and operating the several bits.

A still further object is to provide a removable casing for the head of the boring machine so that the parts will be accessible; and a still further object of my invention is to form stops to regulate the distance the 20 bits may enter the edge of the door.

Referring to the accompanying drawings, in which like references refer to like parts: Figure 1. is a side elevation of my improved boring machine; Fig. 2. is a plan view of the same; Fig. 3. is an end elevation looking from 25 the right hand side of Fig. 1; Fig. 4. is a vertical section on line 4-4 Fig. 3, showing only a portion of the bits; Fig. 5. is a transverse vertical section on line 5-5 Fig. 4; Fig. 6. is an end elevation of one of the 30 guide detached, and Fig. 7. is a perspective view of one of the eccentric sleeves for carrying the guide-rods.

In the accompanying drawings, 1, 2, 3, 4 and 5 represent the bits which are rotatably mounted in the head 6 consisting of the 40 front plate 8 and the rear plate 9, each plate being made in halves, as shown in Figs. 3 and 5, which are held together by screws 10. The adjacent surfaces of the 45 said plates have recesses formed therein to receive the shanks of the bits and form bearings for the same, which bearings may be readily separated by removing the screws 10 to facilitate in assembling or removing 50 the bits. The screws 10 also hold in place the casing 12, which is made in halves and said casing is made of sufficiently heavy metal to hold the front and rear plates 8 and 9 rigidly together, at the proper dis-

tance apart and thus form a substantial and 55 rigid head, when the parts are bolted together.

The shank of the center bit 3 extends beyond the front head 8 and is provided with a squared end for attaching means for rotating the same. The shank of the center bit is made in two parts or sections to permit the sprocket-wheels 14 and 15 to be slipped on the shank and the parts of the shank are then secured together by the sleeve 16. 60

The bits 1, 2, 4 and 5 are rotated by sprocket-chains 18, as shown in Figs. 4 and 5. The sprocket-wheel 14 on the center bit 3 drives the sprocket-wheel 20 on the bit 5. The sprocket-wheel 15 on the center bit 5 70 drives the sprocket-wheel 21 on the bit 1 which latter is provided with a second sprocket-wheel 22 which drives the sprocket-wheel 23 on the bit 4, which latter has a second sprocket-wheel 24 which drives the 75 sprocket-wheel 25 on the bit 2.

By connecting the bits in the above described manner the bits may be placed very close together for the reason that the sprocket-wheels on adjacent bits are not in 80 the same plane, thus permitting larger sprocket-wheels to be used to reduce the friction and all the bits can be rotated in the same direction.

The bits are prevented from moving longitudinally through the plates 8 and 9 of the head by the hubs 30 of the sprocket-wheels, where the latter are located adjacent to said heads, and by collars 31 where the sprocket-wheels are not in a position to prevent longitudinal movement of the bits. 85

The guide-plates 32 and 33 which embrace the door 34, for the purpose of bringing the bits to the center of the latter, are carried by rods 35, 36, 37 and 38; the ends 95 of which are secured in the bosses 39 of the guide-plates by pins 40, which enter annular recesses in the guide-rods, so that the latter may turn freely. The guide-rods are eccentrically mounted in sleeves 42, one of 100 which is shown detached in Fig. 7. The said sleeves have bearing surfaces 43 and 44, which are rotatably mounted in recesses formed in the bosses 45 on the front and rear plates 8 and 9 of the head. Each sleeve 105 42 is provided with a gear-wheel 46 secured at the front end of the head and with a collar 47 secured on the sleeve at the out-

side of the rear-plate 9, thus preventing longitudinal movement of the sleeve.

The gear-wheels 46 on the sleeves mesh with a larger gear-wheel 50 loosely mounted 5 upon the shank of the center bit 3, which in turn meshes with a driving pinion 51 secured on a shaft 52, mounted in the bearing plate 53 secured to the front plate 8. The shaft 52 is provided with a thumb-nut 10 54. By rotating said thumb-nut the center gear-wheel 50 is rotated by the pinion 51 which in turn rotates the gear-wheels 46 secured to the sleeves 42 and as the guide- rods are eccentrically mounted in said 15 sleeves they will be moved simultaneously toward or away from the door to accommodate doors of different thicknesses and always keep the bits centered between the guide-plates carried by the guide- rods.

20 Adjustable stops 55 are mounted upon the guide- rods and the latter are graduated to inches so that the distance that the bits enter the door may be regulated.

25 The guide-plates clamp the door sufficiently tight to center the bits, but they will move upon the surface of the door as the bits enter the latter.

Having thus described my invention I claim and desire to secure by Letters Patent:

30 1. In a boring machine the combination of a plurality of bits, a head carrying said bits, sleeves rotatably mounted in said head, a guide-rod eccentrically mounted in each 35 of said sleeves, a guide-plate located at each side of said bits, said guide- rods rotatably mounted in said guide-plates, gear-wheels upon said sleeves, a centrally located gear-wheel meshing with said gear-wheels upon 40 said sleeves and means for rotating said centrally located gear-wheel.

2. In a boring machine the combination of a plurality of bits, a head carrying said bits, sleeves rotatably mounted in said head, 45 a guide-rod eccentrically mounted in each of said sleeves, a guide-plate located at each

side of said bits, said guide- rods rotatably mounted in said guide-plates, gear-wheels upon said sleeves, a centrally located gear-wheel meshing with said gear-wheels upon 50 said sleeves, a pinion mounted on said head and meshing with said centrally located gear-wheel, and a handle on said pinion for rotating the same.

3. In a boring machine, the combination 55 of a plurality of bits, bearing plates carrying said bits, a casing extending between said plates, guide rods eccentrically mounted in said plates and means for rotating said guide rods.

4. In a boring machine, the combination 60 of a head consisting of two plates, a bit mounted in said plates, sleeves mounted in said plates at either side of the said bit, guide rods eccentrically mounted in said 65 sleeves and means for rotating said sleeves.

5. In a boring machine, the combination 70 of two plates, a casing between said plates, a bit mounted in said plates, said plates made in two sections, fastening devices for securing said sections together, guide rods eccentrically mounted in said plates and means for rotating said guide rods.

6. In a boring machine, the combination 75 of a plurality of bits, plates forming bearings for said bits, a casing between said plates, sprocket wheels upon said bits, sprocket chains upon said wheels, means for rotating one of said bits and thereby rotating the other bits, sleeves mounted in said 80 plates, guide rods eccentrically mounted in said sleeves, gear wheels upon said sleeves, and a gear wheel meshing with all the gear wheels upon said sleeves, and guide plates carried by said guide rods.

85 In testimony whereof I affix my signature in presence of two witnesses.

DANIEL P. JORDAN.
